UNITED STATES PATENT OFFICE

2,487,570

VENTILATION SYSTEM

Alexander Martin, Dedham, Mass., assignor, by
mesne assignments, to Westinghouse Electric
Corporation, a corporation of Pennsylvania

Application January 18, 1946, Serial No. 641,900

1 Claim. (Cl. 98—33)

1

This invention relates to ventilating systems, and relates more particularly to ventilating systems for work rooms in which the air is contaminated by gases such as fumes and smoke.

In some foundry rooms there are a large number of small moulds which are so low that smoke and fumes exhaust therefrom into the foundry rooms well below the level of the attendants' noses and eyes. For providing workable conditions in such rooms, it has been the practise in the past to ventilate such rooms by forcing large volumes of outdoor air therethrough. For example, in a foundry room 30' x 30' with moulds 24" high, it has been the practise to blow 27,000 cubic feet of air per minute through the room for providing adequate ventilation.

This invention provides high velocity air jets forming an air blanket, projected across an apparatus room below the head levels of attendants standing therein, which air blankets prevent the fumes and smoke from the moulds from rising to the head level of the attendants, and which entrain and exhaust the fumes and smoke. In a foundry room in which it has been the practise in the past to supply 27,000 cubic feet of air per minute for providing adequate ventilation, this invention provides better conditions with only 6,000 cubic feet of air per minute.

An object of the invention is to reduce the volume of air required for properly ventilating a room in which gases such as fumes and smoke are exhausted at low levels.

The invention will now be described with reference to the drawing, of which:

Fig. 1 is a diagrammatic view of a foundry room equipped with a ventilating system embodying this invention, the view being a plan view looking downwardly upon the room;

Fig. 2 is a diagrammatic side elevation of the foundry room of Fig. 1, and

Fig. 3 is an enlarged view of a portion of one of the air projection pipes of the system, the view being taken along the lines 3—3 of Fig. 1.

The foundry room illustrated has the large number of spaced, metal moulds 10 which, by way of example, may be 18" x 18" and 24" high. The foundry room may be 30' x 30'. The two air compressors 11 are, in the embodiment illustrated, located outside the room on opposite sides thereof, and their outlets 12 are connected through the sides of the room into the air discharge pipes 13, the inner faces of which extend parallel to each other and which contain the spaced apertures 14 forming air outlets for projecting high velocity, air jets therefrom as will

be described. The inlets 15 of the compressors are open to outdoor air.

The exhaust duct 16 extends across the room parallel to, and equally spaced from, the pipes 13, and is connected to the inlet 17 of the exhaust fan 18. The outlet 19 of the fan 18 discharges into the atmosphere.

The exhaust hood 20 extends over the upper, open end 21 of the duct 16, and has the sloping sides 22 which form with the outer edges of the duct, air entrance slots which may be about 2" wide, and which extend the length of the exhaust duct and hood on both sides thereof.

The lower ends of the sloping sides 22 of the hood 21, terminate just above a plane extending through the axes of the apertures 14 of the pipes 13, whereby the air projected through the apertures moves in substantially a horizontal plane to the hood 21 to be drawn in under the sides 22 thereof.

The apertures 14 may be located about 40" from the floor of the foundry room whereby the air blanket formed by the air projected from the apertures, extends well below the breathing level of the workmen in the room.

In operation, each air compressor 11 may, by way of example, supply 1200 cubic feet of air per minute through the pipes 13 and apertures 14 into the room. The apertures may be one-fourth inch in diameter and spaced 2" apart whereby the air may be projected therethrough at 18,000 feet per minute velocity. The high velocity jets of air are projected towards the exhaust hood 20 and are drawn therein through the previously described slots by the suction of the fan 18.

The fan 18 may be operated to draw in 6,000 cubic feet of air per minute at 500' per minute velocity through the said slots, the volume of 40 6,000 cubic feet per minute being made up by the 1200 cubic feet provided by each compressor 11, and by 3,600 cubic feet of additional air drawn in from the upper area of the room, and supplied through infiltration or through the upper openings 25 or otherwise.

The air projected from the pipes 13, and drawn in at the hood 20 forms an air blanket which prevents the fumes and smoke from the moulds 10 from rising to the head level of workmen in the room, and which entrains the fumes and smoke and exhausts them through the hood from the room. The other air drawn in from overhead provides adequate ventilation.

While one embodiment of the invention has been described for the purpose of illustration,

it should be understood that the invention is not limited to the exact apparatus and arrangement of apparatus illustrated, as modifications thereof may be suggested by those skilled in the art without departure from the essence of the invention.

What is claimed is:

Ventilating apparatus for an enclosure having a plurality of low, gas emitting containers therein, said containers emitting gas into said enclosure at levels well below the head levels of attendants standing therein, comprising air discharge pipes extending crosswise said enclosure substantially the full width thereof at opposite sides of said containers, air compressors having 15 their outlets connected to said pipes so as to supply compressed air thereto, said pipes having in their sides which face said containers means for projecting air at high velocity thereover, an exhaust hood extending crosswise said enclosure between said pipes, a fan having its inlet connected to said hood, said hood having in its sides which face said pipes air inlet means for drawing thereto at high velocity the air projected from said pipes, said air projecting means in said pipes and said air inlet means in said hood extending above said containers but below the head levels of said attendants stand- 20 25

ing in said enclosure, said enclosure having an air inlet opening therein above said pipes and hood, said fan having a capacity greater than that of said compressors whereby some of the air drawn from said enclosure through said hood is drawn into said enclosure through said air inlet opening.

ALEXANDER MARTIN.
